S. LANDER.

TOY GUN.

APPLICATION FILED JUNE 14, 1921.

Patented May 23, 1922.

UNITED STATES PATENT OFFICE.

SAMUEL LANDER, OF SUTERSVILLE, PENNSYLVANIA.

TOY GUN.

1,417,392.

Specification of Letters Patent. Patented May 23, 1922.

Application filed June 14, 1921. Serial No. 477,527.

To all whom it may concern:

Be it known that I, SAMUEL LANDER, a citizen of the United States, residing at Sutersville, in the county of Westmoreland 5 and State of Pennsylvania, have invented new and useful Improvements in Toy Guns, of which the following is a specification.

This invention relates to toy guns, and more particularly to a gun of the machine 10 or rapid fire type.

One of the main objects of the invention is to provide a gun of the character stated of simple construction and operation which may be readily produced at small cost. A 15 further object is to provide a gun including projecting means and means actuated by the projecting means for supplying projectiles successively to the gun, the projectiles being normally held within a casing 20 or magazine so as to prevent loss thereof. Further objects will appear from the detailed description.

In the drawings:

Figure 1 is a side view of a gun constructed in accordance with my invention 25 partly broken away;

Figure 2 is a back view of the same;

Figure 3 is a detail, partly in section, of the breech block and associated parts;

Figure 4 is a section taken substantially 30 on line 4-4 of Figure 3;

Figure 5 is a detail of the breech block and associated parts, partly in section, showing a modified form of magazine;

Figure 6 is a fragmentary side view of the modified form illustrated in Figure 5.

Figure 7 is a section taken substantially 35 on line 7-7 of Fig. 3.

Figure 8 is a section taken substantially 40 on line 8-8 of Fig. 3.

For supporting the gun I provide a base plate 1 to which are secured two side plates 2 which support a platform 3. A barrel 4 is provided with a block 5 which is secured 45 upon platform 3, this barrel having an axial bore 6. The barrel is further provided in its rearward end with a vertically extending slot 7 which communicates at its lower end with bore 6, and with a lower vertical slot 8 extending from the lower portion of the bore.

The projecting means includes a striker 9 of substantially L-shape which is rockably mounted upon a shaft 10 extending through 50 side walls or plates 2. The rearward arm 11 of this striker is adapted to fit into slot

8 and to contact with a projectile positioned in the bore of the barrel and projecting rearwardly of the same, for propelling the projectile from the gun. The forward arm 12 60 of striker 9 is connected by a tension spring 13 to base plate 1 and acts to normally hold the striker with arm 11 in vertical position and arm 12 in horizontal position. For operating the striker I provide a shaft 14 65 rotatably mounted through plates 2 and provided at one end with a crank-handle 15. This shaft is formed from a suitable length of steel wire, or a rod, which is bent to produce two oppositely directed cranks 16. 70 The shaft 14 is positioned in advance of striker 9 and the cranks 16 are of such length that when the shaft is rotated in a clockwise direction the cranks will contact with the underface of arm 12 raising this arm 75 into the position illustrated in Figure 1 thus tensioning spring 13, after which the crank passes out of contact with arm 12 permitting the striker to be returned to its initial position by the spring and causing the upper 80 portion of arm 11 to strike the end of a projectile 17 positioned within the rearward portion of bore 6, thus driving or propelling the projectile from the barrel 4. This provides simple and efficient means whereby the 85 striker may be readily operated at high speed.

For supplying the projectiles to the barrel I provide a magazine 18 of rectangular cross-section, this magazine being readily formed 90 by stamping and pressing from a single piece of sheet metal. The magazine 18 is positioned in alignment with slot 7 and is secured to block 5 by means of a tab 19 extending from the lower end of one side wall of the 95 magazine, this wall being provided adjacent to its upper end with a transversely extending slot 20 by means of which the projectiles 17 may be readily inserted into the magazine. At the upper end of side wall 18^a of 100 the magazine, the sheet metal is turned over at right angles and is then bent downwardly at right angles to provide a side wall 21 which is separate from the front and back walls 22 and 23, respectively, this side wall 105 being connected at its upper end, by an arm 21^b, to upper portion 18^b of wall 18. This wall 21 has its lower portion bent inwardly toward wall 18^a, and extended downwardly within slot 7. Due to its inherent resiliency, 110 wall 21 presses toward wall 18^a so that the lower inwardly directed portion 21^a of this

wall serves to effectually prevent downward movement of the projectiles 17, and co-operates with wall 18^a to grip the projectiles, as illustrated. By moving portion or element 21^a of wall 21 outwardly the projectiles are released so as to move downwardly in the magazine, the lowermost projectile dropping into the rearward portion of bore 6, it being understood that the magazine is so positioned that the rearward end of this projectile extends rearwardly a short distance into vertical slot 8 so as to be struck by arm 11 when the striker 9 is released. Normally the projectiles will be retained in the magazine so as to effectually prevent loss of the projectiles due to the same falling into the barrel 4 from the magazine.

For feeding the projectiles from the magazine into the barrel I provide an angle lever 24 pivoted on a bracket 25 secured on platform 3, the vertical arm 24^a of this lever being connected by a rod 25' to element 21^a adjacent to the lower end thereof. This rod passes through a bore 26 provided in the breech block for this purpose, and slot 7 is extended toward lever 24 sufficiently to permit movement of element 21^a into and out of operative position. The other arm of lever 24 is connected by a link 27 to the outer end of a lever 28 which is pivoted intermediate its ends in a bracket 29 secured to one of the side plates 2. This lever projects through a slot through the side plate and has its inner end connected by a cord 35 or cable 30 to arm 12 of striker 9. The cable 30 is of such length that when the striker is moved into substantially fully retracted position, as in Figure 1, the cable is tensioned thus rocking arm 24^a of lever 24 outwardly so as to move element 21^a into the position indicated in Figure 3. This serves to completely open the lower end of magazine 18 permitting the projectiles 17 to move downwardly in the magazine, the lowermost projectile being discharged from the magazine into the bore 6 of barrel 5 at the rearward end thereof in such position as to be acted upon by arm 11 of the striker when the latter is released so as to be projected from the gun. This provides simple and efficient means whereby the projectiles are normally retained within the magazine so as to prevent loss of the projectiles, the projectiles being fed from the magazine into the barrel during operation of the firing or projecting means.

In the modified form of magazine illustrated in Figures 5 and 6, I provide a wire frame or magazine 31 one arm 31^a of which is secured to the block 5, the other arm 31^b being inclined downwardly and inwardly toward arm 31^a, and having its lower end portion turned outwardly at right angles to provide a connecting element 25^a corresponding to rod 25'. At its upper end the magazine

31 is provided with an enlargement or eye 32 to permit projectiles 33 to be inserted between arms 31^a and 31^b, each of these projectiles being provided with a circumferential groove 34 for reception of arms 31^a and 31^b these arms serving to prevent endwise movement of the projectiles through the magazine, and arm 31^b serving to prevent downward movement of the projectiles beyond the lower end of the magazine. The operation of the modified form of magazine is similar to the operation of the magazine illustrated in Figures 1 to 4.

A tension spring 28^a is preferably, though not necessarily, provided for returning arm 24 of lever 24 to normal position, this spring being secured at its upper end to plate 2 and, at its lower end, to lever 28. By providing wall 21 of magazine 18 with sufficient strength and resiliency to return the lever 24 and associated parts to normal positions, the spring 28^a may, if desired, be omitted.

As will be understood, and as indicated herein, changes in details of construction and arrangement of parts of the invention may be resorted to without departing from the field and scope of the same, and I intend to include all such variations, as fall within the scope of the appended claims, in this application in which the preferred forms only of my invention are disclosed.

What I claim is:—

1. In a toy gun, a barrel provided with a slot communicating with the bore of the barrel, a magazine communicating at its discharge end with said slot and including two members for confining between them projectiles, one of said members being resilient and normally pressing inwardly toward the other member to prevent discharge of the projectiles from the magazine, projecting means positioned to act upon projectiles discharged from the magazine into the barrel, and means actuated by said projecting means for causing outward movement of said resilient member for feeding the projectiles from said magazine into the barrel.

2. In a toy gun, a barrel provided with a slot communicating with the bore of the barrel, a magazine communicating at its lower end with said slot and including two members positioned to confine between them projectiles, one of said members being resilient and normally pressing inwardly toward the other member to prevent downward movement of the projectiles, projecting means positioned to act upon projectiles discharged from the magazine into the barrel, and means actuated by said projecting means for causing intermittent outward movement of said resilient member for successively feeding the projectiles from the magazine into the barrel during operation of the projecting means.

3. In a toy gun, a barrel provided with a

slot communicating with the bore of the barrel, a magazine communicating at its lower end with said slot and including two members positioned to confine between them projectiles, one of said members being resilient and normally pressing inwardly toward the other member to prevent downward movement of the projectiles, a striker positioned to act upon projectiles discharged into the barrel from the magazine, means for forcing the striker toward the barrel, means for retracting and subsequently releasing the striker, and means for causing outward movement of said resilient member so as to release the lowermost projectile and permit the same to drop into the bore of the barrel as the striker approaches fully retracted position.

4. In a toy gun, a barrel, projecting means, a magazine positioned to discharge projectiles into the barrel in position to be acted upon by the projecting means, the

magazine being provided with co-acting members acting to grip between them the projectiles of a stack of projectiles placed in said magazine, and means for operating the projecting means and for releasing the lowermost projectiles of the stack so as to permit discharge thereof into the barrel.

5. In a toy gun, a barrel, projecting means, a magazine positioned to discharge projectiles into the barrel in position to be acted upon by the projecting means, the magazine being provided with means for gripping the projectiles of a stack of projectiles placed in said magazine, and means for operating the projecting means and for releasing the lowermost projectiles of the stack so as to permit discharge thereof into the barrel.

In testimony whereof I affix my signature.

SAMUEL LANDER.
